UNITED STATES PATENT OFFICE.

EDWARD N. JACOBI, OF MILWAUKEE, WISCONSIN, ASSIGNOR, BY MESNE ASSIGNMENTS, TO BRIGGS & STRATTON CORPORATION, OF MILWAUKEE, WISCONSIN, A CORPORATION OF DELAWARE.

HORN PUSH BUTTON.

Application filed August 27, 1920. Serial No. 406,290.

This invention relates to push buttons and particularly to push buttons for controlling horn circuits of automobiles.

An object of the invention is to so simplify the construction that the device may be made durable and efficient and at the same time inexpensive to manufacture.

With the above and other objects in view the invention consists in the push button as herein claimed and all equivalents.

Referring to the accompanying drawings in which like characters of reference indicate the same parts in different views:

Fig. 1 is a front view of a push button constructed in accordance with this invention;

Fig. 2 is a rear view thereof on a larger scale;

Fig. 3 is a sectional view thereof;

Fig. 4 is a rear view of the insulating disks; and

Fig. 5 is a view of the spring cup showing the square post connection therewith.

In these drawings 10 indicates a casing ring of sheet metal forming an inturned button retaining flange and an outwardly extending attaching flange with downwardly turned edges and provided with openings 11 to receive attaching screws.

20 A sheet metal retaining ring 12 fits in the recess in the back of the securing flange where where it is secured in place by three small crimps 13 made in the edge of the securing flange. Notches 14 are formed in the ring 12 to receive the depressions forming the screw holes 11 while the inner edge is bent up to form an outwardly extending flange 15 for strengthening purposes.

The diameter of the opening in the retaining ring 12 is less than the diameter of the cylindrical portion of the casing ring 10 so as to form a shoulder for retaining the parts within the casing ring.

45 A cup-shaped button member 16 of insulating material loosely fits within the casing ring with a beveled shoulder normally bearing against the conical button retaining flange thereof.

50 A sheet metal cup 17 is mainly contained within the cavity in the back of the push button 16 but its outwardly extending flat edge bears against the flat end of the button 16 and constitutes an annular contact normally spaced from, but capable, when the

button is depressed, of engaging a cooperating annular contact flange of a sheet metal contact ring 18 held within the casing and insulated therefrom by insulating ring 19 bearing against the retaining ring 12. The contact ring 18 has an inwardly extending flange 20 for retaining within it an insulating member 21, as here shown consisting of three fiber disks, serving as a spring seat for a coil spring 22 which is confined between it and the cup 17 to keep the contacts separated. The thrust of the spring in one direction is taken by the outwardly extending flange of cup 17 bearing against the end of button 16 and the shoulder of button 16 bearing against the in-turned flange of the casing, while the thrust in the other direction is taken by the insulating member 21 bearing against the in-turned flange 20 of contact ring 18 and the outward turned flange of the latter bearing against insulating ring 19, which in turn is bearing against the retaining ring 12 secured to the casing.

In order to make electrical connection with the cup 17 a post 23 is secured thereto and passes freely through an opening 24 in the insulating member 21 with a screw 25 threaded in its end to form a binding post. As here shown, the post 23 is square in cross section and fits in the correspondingly shaped opening 24 in the insulating disks 21 to serve as a key for preventing parts from turning. Preferably also, the post is so connected with the cup 17 as to prevent its turning with respect thereto, and with this end in view, it is shown as having a reduced neck turned therein, as seen in Figs. 3 and 5, which is passed through a toothed opening 26 in the cup 17 and is then spread by forcing a conically shaped tool in the end of the opening which extends through it, thus flaring or upsetting the end of the post and crowding the neck portion into the teeth of the opening to effectively rivet the post in a manner that will prevent it from turning.

In order that electrical connection may be made with the contact ring 18 the flange 20 is broadened at one part and bent outwardly to form a nut housing with a substantially square recess 27 in the outer insulating disk 21. This nut housing encloses a nut 28 and a screw 29 passes through an opening in the flange 20 and threads through the nut and extends into a circular opening 30 in the

next insulating disk. The nut is thus retained and prevented from turning by the enclosure provided for it and the screw 29 forms a binding post.

3. In operation the horn circuit or other circuit controlled by the push button is normally interrupted because of the spaced relation in which the contacts 17 and 18 are held but a pressure on the button 16 either to slide or tilt it serves to move the contact 17 against the action of spring 22 into contact with the flange of contact ring 18 to close the circuit. This movement is attended by a movement of the binding post 23 attached to contact 17, which of course is permitted by the flexibility of the lead wire connected therewith. As soon as pressure is released from the button the spring returns contact 17 to its normal position to break the circuit.
20. It will be noted that the parts are well insulated so that there is no danger of short circuit and that the entire switch mechanism is condensed in a very small space, making it convenient to locate the button wherever desired. The nut members of both binding posts are prevented from turning, making it easy to connect the wires thereto.

The entire construction is strong and durable and is not liable to get out of order, though it is inexpensive to manufacture. The broad annular contact made between the contact members is one which offers low resistance to the circuit established and which, because of the slight play between the parts, will have its contact surfaces wear clean at all times.

The invention is not limited to specific form and arrangement of parts, except in so far as such limitations are specified in the claims.

What I claim as new and desire to secure by Letters Patent is:

1. In a push button a pair of annular contacts, an insulating member within one contact, a stem eccentrically positioned on the other contact passing through an opening in the insulating member and forming a binding post, and a binding post formed on the first mentioned contact and engaging the insulating member to prevent it from turning.
2. In a push button, a pair of annular contacts, an insulating member held within one contact, a stem mounted on the other contact and passing through an opening in the

insulating member and forming a binding post, a spring surrounding the stem and bearing on the insulating member and on the said other contact, there being a recess in the insulating member, a flange on the first mentioned contact forming a nut housing with the said recess, a nut within the nut housing, and a screw passing through the flange and threaded in the nut to constitute a binding post.

3. In a push button, a cup-shaped contact and a ring-shaped contact, both having annular flanges to form contact surfaces, an insulating member fitting within the ring-shaped contact, a stem on the cup-shaped contact passing through the insulating member and forming a binding post, and a spring surrounding the stem and bearing on the cup-shaped contact and on the insulating member.

4. In a push button, a casing having an in-turned edge, an insulated button member slidable in the casing and provided with a shoulder bearing against the in-turned edge of the casing, a cup-shaped contact member bearing against the button member, a ring-shaped contact provided with an outwardly extending flange and an inwardly extending flange, an insulating member contained within the ring-shaped contact and bearing against the in-turned flange, an insulating ring around the ring-shaped contact engaged by the outwardly extending flange, a retaining ring secured to the casing and engaging the insulating ring, a stem on the cup-shaped contact passing through the insulating member and forming a binding post, a spring surrounding the stem and bearing on the insulating member and on the cup-shaped contact, and a binding post on the in-turned flange of the ring-shaped contact formed by a screw passing through said flange and a nut threaded on the screw and contained in the recess of the insulating member.

5. In a push button, a sheet metal contact member provided with a toothed opening, a stem secured thereto by having a reduced portion passed through the opening and upset against the teeth of the opening to prevent it from turning, and a screw threaded in the stem to form a binding post.

In testimony whereof, I affix my signature.

EDWARD N. JACOBI.
